UNITED STATES PATENT OFFICE

161,054

PAPER DISPENSER

Stanley J. Rutka, Gheen, Minn.

Application May 21, 1949, Serial No. 2,801

Term of patent 14 years

(Cl. D4—3)

To all whom it may concern:

Be it known that I, Stanley J. Rutka, a citizen of the United States of America, residing at Gheen, county of St. Louis, and State of Minnesota, have invented a new, original, and ornamental Design for a Paper Dispenser, of which the following is a specification, reference being had to the accompanying drawing, forming a part thereof.

In the drawing:

Fig. 1 is a perspective view of a paper dispenser, showing my new design, the dispenser being in open position.

Fig. 2 is a front elevational view of the dispenser shown in Fig. 1, the dispenser being in closed position.

Fig. 3 is a side elevational view of Fig. 2.

I claim:

The ornamental design for a paper dispenser, as shown.

STANLEY J. RUTKA.
